UNITED STATES PATENT OFFICE

100,876

DESIGN FOR A CANDLE LAMP

Thomas J. Muench and Oscar D. Guilfoil, Syracuse, N. Y., assignors to Muench-Kreuzer Candle Company Inc., Syracuse, N. Y., a corporation of New York

Application January 24, 1936, Serial No. 60,795

Term of patent 14 years

To all whom it may concern:

Be it known that we, Thomas J. Muench and Oscar D. Guilfoil, citizens of the United States, residing at Syracuse, in the county of Onondaga and State of New York, have invented a new, original, and ornamental Design for a Candle Lamp, of which the following is a specification, reference being had to the accompanying drawing forming part thereof.

The drawing is a perspective view of a candle lamp embodying our new design.

The appearance of the opposite side is substantially the same as the side shown.

We claim:—

The ornamental design for a candle lamp substantially as shown and described.

THOMAS J. MUENCH.
OSCAR D. GUILFOIL.
